(57) **CLAIM**

The ornamental design for hand held electronic temperature measuring device, as shown and described.

DESCRIPTION

FIG. 1 is a front elevational view thereof;

FIG. 2 is a rear elevational view thereof;

FIG. 3 is a top plan view thereof;

FIG. 4 is a bottom plan view thereof;

FIG. 5 is a left side elevational view thereof; and,

FIG. 6 is a right side elevational view thereof.

The broken lines in the drawings are for the purpose of illustrating portions of the hand held electronic temperature measuring device that form no part of the claimed design.

1 Claim, 6 Drawing Sheets

FIG. 1

FIG.2

FIG.3

FIG.4
